US00D752803S

(12) **United States Design Patent**
Reyes

(10) **Patent No.:** **US D752,803 S**
(45) **Date of Patent:** **** Mar. 29, 2016**

(54) **LIGHT FIXTURE**

(71) Applicant: **Jaime A. Reyes**, Miami Lakes, FL (US)

(72) Inventor: **Jaime A. Reyes**, Miami Lakes, FL (US)

(**) Term: **14 Years**

(21) Appl. No.: **29/504,807**

(22) Filed: **Oct. 9, 2014**

Related U.S. Application Data

(63) Continuation-in-part of application No. 29/490,948, filed on May 15, 2014, now Pat. No. Des. 728,848.

Induction Grow Light Fixture, image post date 2014, site visited Aug. 23, 2015, (online), <http://www.cashinbis.com/products/indagro-pro-420-par-induction-grow-light-fixture>.*

Primary Examiner — Kevin Rudzinski

Assistant Examiner — Sean D Lough

(74) *Attorney, Agent, or Firm* — Malloy & Malloy, P. L.

(57) **CLAIM**

The ornamental design for the light fixture, as shown and described.

DESCRIPTION

FIG. 1 is a top perspective view illustrating my design of a light fixture with a junction bar shown in broken lines included as environment forming no part of the claimed design;

FIG. 2 is a right side view of the light fixture depicted in FIG. 1;

FIG. 3 is a left side view of the light fixture depicted in FIG. 1;

FIG. 4 is a front view of the light fixture depicted in FIG. 1; FIG. 5 is a rear view of the light fixture depicted in FIG. 1; FIG. 6 is a top view of the light fixture depicted in FIG. 1; FIG. 7 is a bottom view of the light fixture depicted in FIG. 1 with a light bar shown in broken lines included as environment forming no part of the claimed design; and,

FIG. 8 is a bottom perspective view of the light fixture depicted in FIG. 1 including the environment of FIG. 7 that forms no part of the claimed design.

The broken lines (where present) throughout all Figures illustrate portions of the light fixture that form no part of the claimed design.

1 Claim, 6 Drawing Sheets
